UNITED STATES PATENT OFFICE.

CHARLES W. CROWELL, OF SALISBURY, NORTH CAROLINA.

STEAM-BOILER.

1,115,787.

Specification of Letters Patent.

Patented Nov. 3, 1914.

Application filed April 5, 1911. Serial No. 619,051.

To all whom it may concern:

Be it known that I, CHARLES W. CROWELL, a citizen of the United States, and a resident of Salisbury, county of Rowan, and State of North Carolina, have invented certain new and useful Improvements in Steam-Boilers and Appliances, of which the following is a specification:

This invention is an improvement in steam boilers, and especially in boilers for use on locomotives, and the invention consists in certain novel constructions and combinations of parts for the purpose of economizing in building and repairing boilers, for reducing the fuel consumption and for preventing damage by fires, as will be hereinafter described and claimed.

In the drawings which are for the purposes of illustration only Figure 1 is a vertical longitudinal section of a boiler embodying my invention. Fig. 2 is a front elevation of the boiler. Fig. 3 is a cross section enlarged on about the line 3—3 of Fig. 1, Fig. 4 is a cross section on about the line 4—4 of Fig. 1, Fig. 5 is a rear end elevation partly in section. Fig. 6 is a detail section enlarged of the main combustion chamber. Fig. 7 is a detail perspective view of the mud frame with some of the stay rods in connection with the cross bar thereof. Fig. 8 is a detail vertical longitudinal section enlarged, showing the means for staying the extension of the top plate of the main combustion chamber to the flue sheet of the fire box. Fig. 9 is a detail section on about the line 9—9 of Fig. 1. Fig. 10 is a sectional view showing a somewhat different construction from that presented in Fig. 1. Fig. 11 is a cross section on about line 11—11 of Fig. 10. Fig. 12 is a detail perspective view of the partition plate shown in Figs. 10 and 11. Fig. 13 shows a somewhat different arrangement of the combustion chamber from that shown in the other figures of the drawings.

In carrying out the invention, I provide a fire box A having a suitable grate B and an ash pan C, and the boiler is provided with flues D, and with heads D' and D'', the head D'' forming the back wall of the smoke box D', and the head D' forming the inner end plate of the fire box A. At its rear end, the boiler is extended upwardly at D⁴ above the level of the body of the boiler and over the fire box A, so that the flues D can extend to the top of the body of the boiler, the upward extension D⁴ affording a means for the

storage of water and steam so that even the uppermost flues D can always be covered with water in the use of the invention. In connection with the flues D, I provide what, for convenience of reference, I term the main combustion chamber E, and the intermediate combustion chamber F, the latter being disposed between the combustion chamber E and the smoke box D'.

The flues D are arranged in series 1, 2 and 3. The flues of the series 1 carry the flames and gases from the fire box forwardly into the smoke box D', whence they are conducted rearwardly through the flues of the series 2, into the main combustion chamber E, and they pass thence through the flues of the series 3 into the smoke chamber at the base of the stack 4, and thence into stack 4 whence they may be discharged in a manner described more fully hereinafter.

It is preferred to provide the flues of the series 1, 2 and 3 into front and rear sections, as best shown in Fig. 1, and to connect the adjacent ends of the two sections of each series 1, 2 and 3 by means of the intermediate combustion chamber F. This intermediate combustion chamber is circular in cross section, as shown in Fig. 9, and is divided into three chambers F', F² and F³, which are separated by cross plates F⁴ having openings F⁵, and removable plates F⁶ covering the same, so that communication may be had through a man hole F⁷ at the bottom of the intermediate chamber and man holes in the plates F⁴ to the different compartments of the intermediate chamber in order to repair the flue connections, or for any other purpose, as may be desired.

The heads in front and rear of the intermediate combustion chamber are provided surrounding such chamber with openings F⁸ to permit the circulation of the boiler water, and the said heads are cut away at F⁹ at opposite sides of the manhole F⁷, as best shown in Fig. 9, to permit the circulation of water below the intermediate combustion chamber and surrounding the tubular manhole F⁷ for obvious purposes.

The main combustion chamber E is circular in cross section, as best shown in Fig. 4, and has front and rear heads, the rear head being braced from the flue sheet D' by stay rods D¹¹, and the cylindrical body of the combustion chamber E being extended rearwardly at E', as shown in Fig. 6 to abut at its rear edge the flue sheet

D', the rear edge of the extension E' being notched at E², as best shown in Fig. 6, to permit circulation of water without interfering with the bracing of the main combustion chamber from the said flue sheet D', as will be understood from Figs. 1, 6, and 8 of the drawings. The rear extension E' may also be provided, as shown in Figs. 1 and 8, on its inner side, with lugs or brackets E³ connected by stays E⁴ with the flue sheet D', in order to steady and brace the main combustion chamber in position, also to strengthen the flue sheet of the fire box in its weakest part insuring it not to warp or buckle. The rear head of this combustion chamber has stay bolts connecting to the flue sheet D also for the same purpose. This main combustion chamber has a downwardly extending tube E⁵ which opens at the lower side of the tubular casting E⁶, and the upper end of the tube E⁵ is formed at the lower side of the chamber E with a nozzle E' to spray air within the combustion chamber E when the valve E⁸ is opened, the said valve being controlled from the locomotive cab by means of a bell crank lever E⁹ connected with the valve E⁸ and a rod E¹⁰ extending to the cab, as will be understood from Fig. 1 of the drawings. By this construction, air may be admitted in any desired quantity to the main combustion chamber, and may be distributed therein by means of the nozzle to the air in feed tube E⁵, as before explained. The main combustion chamber E is provided with a partition partially dividing it into upper and lower sections, and this partition tube G is preferably provided with an adjustable section G', which may be set forward or back to vary the opening between the upper and lower sections of the chamber E in such manner as to regulate the draft and thoroughly mix the gases with air from air tube before it has chance to return into middle series of flues. This adjustable section may be set in building the boiler, or from time to time, as may be necessary.

In the operation of the described features of my invention, it will be noticed that the products of combustion pass from the fire box A forwardly through the tubes of the series 1, through the upper section F' of the intermediate combustion chamber, thence into the smoke box D³, thence back through the lower series 2 of flues into the section F³ of the chamber F, thence back into the lower section of the chamber E, thence forwardly through the flues of the series 3 into the section F² of the intermediate combustion chamber, thence forwardly through the flues into the smoke chamber and stack, whence the products will be discharged in a manner presently described.

In this construction it will be noticed I

provide for extracting practically all the heat energy from the flames and gases and also seek to cause combustion of the unconsumed gases and solid particles accompanying the same after they have left the fire box A, by means of the combustion chamber arranged and operating as before described.

In the smoke box D³ and in front and rear of the exhaust nozzle 5, I provide adjustable cross plates 6 and 7, which may be raised and lowered and utilized to aid in controlling the draft, as will be understood by those skilled in the art.

It will be noticed that the intermediate combustion chamber is stayed from adjacent portions of the boiler by stay rods H, H', H², and H³, as best shown in Fig. 1 of the drawings.

As more fully described hereinafter, the head D' is circular in correspondence with the circular form of the fire box A and the head D' is in registry with the intermediate combustion chamber F and is of the same size as said combustion chamber so that the flues leading from the head D' communicate properly with the intermediate combustion chamber and the said flues fill the front flue sheet to the top, this being rendered practicable as before described by raising the top shell of the boiler high enough to form the water and steam space at D⁴ as before referred to. It will be noticed that the main combustion chamber E is also a circle in cross section, but is of less diameter than the intermediate combustion chamber as only the lower and central flues communicate with the main combustion chamber as before described. This circular form of combustion chambers provides a construction of great strength. By my construction I am also able to make the smoke box at the front of the boiler shorter than those ordinarily used.

The intermediate combustion chamber is found especially useful when it is desired to make a locomotive of extra length as is sometimes the case in boilers designed for furnishing steam for two engines or for a double engine, as the intermediate combustion chamber relieves the excessive length of flues incident to a construction wherein the flues extend continuously between the end sheets of the boiler. Any desired number of these intermediate combustion chambers may be employed. It will be understood also that provision may be made for admitting air to the intermediate combustion chamber, substantially in the same manner as air is admitted to the main combustion chamber E. In the production of this intermediate combustion chamber, the partition plates with their openings and the plates for closing the openings in the partition plates should be made in sections sufficiently

small to enable their application and removal through the opening leading from the outside to the said intermediate combustion chamber.

- 5 The special route of travel of the products of combustion from the fire box to the smoke stack, provides for more flues at the top than in bottom, and more in bottom than in center section, thus concentrating 10 the products in the flues of the central series leading directly to the chamber in the main smoke box below the stack 4 and then to the said stack and it will be noticed also that the flues of the series 1 are longer than 15 the flues of the series 2 or 3 in Fig. 1.

The upward extension and circular form of the outside shell of boiler around the fire box is not only important in that it insures the covering of the top flues at all times, but 20 it also allows me to drop down low enough on the bottom to form an open bottom fire box without a throat sheet or a water leg at the front end of fire box and at the same time allows the stay bolts from fire box to 25 the outside shell to be equally spaced and of an equal length if so desired which will stop stay bolts from breaking and allow me to carry a larger body of hot water for the cold to mix with and making it unnecessary to 30 put water in so often which will avoid chilling when cold water is put in, resulting in the saving of the fire box from cracking and buckling.

The construction as before described, of 35 the main combustion chamber with the rearwardly projecting flange-like structure E' braced from the flue sheet D' is important in that thereby the combustion chamber is braced in position and the flue sheet D' 40 is also stayed and braced as will be understood from the drawings.

The fire box A underlies the upward extension D' of the boiler and this fire box is made circular in cross section as best shown 45 in Fig. 5 and is riveted at its front end at I to the flue sheet D' and is stayed by the stay rods J from the shell of the boiler, which shell of the boiler is cut away at its rear portion throughout the length of the 50 fire box A and receives what, for convenience of reference, I term the mud frame JJ, shown in detail in Fig. 7 and applied in Figs. 1 and 5 of the drawings. The fire box A is also cut away at the bottom to receive 55 the grate bars and to communicate with the ash-pan C. The circular form of the fire box is quite important as it enables me to make the stay bolts or rods J equally spaced apart and renders the construction of the 60 rear end of the boiler easier and facilitates the withdrawal bodily of the fire box whenever desired, by simply cutting off the rivet heads of the rivets I and the stay rods J and the rivet heads at K connecting with the 65 back head of the boiler. If, however, it is

desired to withdraw the flues with the fire box, the rivets I may be left intact and the heads of the stay rods J cut away and the rivets K also cut away and the rivets connecting the front flue sheet D' and intermediate rivets be also cut when the flues and fire box may all be withdrawn together.

The mud frame JJ is made in approximate U-shape with a cross bar J' and with base wings J³ and top wings or flanges J⁴ 70 riveted respectively to the shell of the boiler and the fire box, the rear ends of the said bars of the frame being turned outwardly as best shown in Fig. 7 for connection with the back head L of the boiler shell, the said 80 boiler shell being riveted at L' to the end wings J⁵ of the mud frame, as best shown at the right in Fig. 5 of the drawings.

The mud frame is stayed by the rods J² as shown in Figs. 1 and 7 and also by rods 85 J⁶ extending from the side bars of the frame upwardly to the shell of the boiler, as shown at the left in Fig. 5.

The fire box has at its outer end a doorway A¹⁰ leading through the outer head A¹¹ 90 and the inner head A¹², the said heads being spaced apart forming a water chamber to which the water from the boiler passes through openings A¹³, the said openings A¹³ being formed in the main shell of the fire 95 box and preferably in the outwardly flared portion A¹⁴ thereof, as best shown in Fig. 1 of the drawings.

The back end of the fire box is flared out enough for the rivet heads on inside water 100 space sheet to clear back head when fire box is being put in or taken out. The fire box also is made slightly tapered, being larger at the back end so as to not bind on stay bolts when fire box is being removed.

As best shown in Fig. 1, the end plate or head N of the boiler shell is flanged inwardly at its outer edge at N' for riveting to the boiler shell, and is flanged outwardly at N² at its inner edge for riveting at K to the 110 outer flared end of the fire box.

In the described arrangement of parts, it will be noticed that the mud frame is located down below the fire, thus avoiding the danger of the fire box becoming mud burned and the front end thereof and the boiler space afforded between the fire box and the shell of the boiler at the sides, enables me to dispense with separate water leg constructions at the front end of the fire box as other boilers have.

The round or circular form in cross section of the fire box, is important because it enables me to produce the fire box at the smallest initial expense and at the same time 125 supplies a box which efficiently serves the purpose for which it is designed and has great strength and makes strain on stay bolts more equal.

The spark arresting construction is made 130

large to afford ample space and resembles, in general aspects, the saddle tanks sometimes employed upon locomotive boilers. As shown, the spark arrester comprises what, for convenience of reference, I term a front chamber M , an intermediate chamber M' , an outlet chamber M^2 leading to the stack M^3 and spark or cinder pipes M^4 leading downwardly from the chamber M and communicating with the said chamber at or near the rear end thereof, as will be understood from Fig. 1 of the drawings. As indicated in dotted lines in Fig. 1, the spark or cinder pipes M^4 are in the position to receive sparks or cinders delivered at the sides of any of the chambers M , M' or the stack M^3 . The front end of the chamber M rounds up toward its upper side and immediately above the said chamber M an air inlet opening M^6 is provided leading to a passage M^7 which gradually tapers toward its rear end and discharges air at such end into the chamber M^8 leading to the stack M^3 , a damper M^9 being provided to permit the regulation of such air from the cab of the locomotive. The inlet opening M^6 is intended to increase the draft out of the stack. The chamber M' receives the smoke, etc., at M^{11} from the chamber M and an adjustable plate M^{12} may be set to regulate the opening between the chambers M and M' and a similar plate M^{13} may be provided to control the communication between the chambers M' and M^8 , a relief pipe M^{10} leading from the rear end of the chamber M' forwardly to the chamber M^2 to relieve pressure at the back end of the chamber M' when necessary and this relief pipe M^{10} is controlled by a valve or damper M^{14} which may be operated from the cab of the locomotive or may be held in any suitable position by the aid of the rack M^{15} , as will be understood from Fig. 1 of the drawings. In the operation of this spark arrester, it will be noticed that the sparks from the stack 4 of the smoke box will be delivered into the chamber M thence into the chamber M' and thence into the chamber M^8 on the way to the outlet stack M^3 , any cinders or sparks settling at the sides of any chambers M , M' or M^2 passing down to the cinder pipes M^4 and thence to the ash pan, the pipes M^4 being controlled by dampers M^{16} from the cab as will be understood from the drawings. These dampers M^{16} in the spark pipes are also for the purpose of regulating the draft into the pan from the spark arrester. In the use of the described construction, it will be understood, wood, coal or other forms of fuel may be employed.

The large water space on each side of the fire box affords a means for preventing the boiler from becoming chilled when water is put into it. That is to say, the large volume of hot water contained in the water spaces just mentioned may be mixed with a consid-

erable quantity of cold water and still remain at a fairly high temperature, so that the fire box is not liable to crack as is sometimes the case where narrow water legs are used. My fire box, owing to its curvature upwardly and outwardly from the grates, has a tendency to prevent cold air from striking the fire box from below, and on this account prevents the fire box from buckling, cracking or leaking at the stay belt as is too commonly the case with boilers heretofore used.

Practically speaking, I combine a spark arrester and spark extinguisher by returning the exhaust back from stack 4 toward the rear into another chamber, then forward and back through last chamber to stack M^3 . I hold and mix the exhaust and sparks together in such a way they are extinguished should any of them go out of the stack, avoiding setting out fires on the right of way.

I afford ample ventilation to my spark arrester, avoiding a back pressure in stack 4 or any of the chambers by means of large pipes made in convenient shape on each side, allowing cinders and gases or substances to enter ash pan below grates having a chance to burn any unconsumed gases which draft is controlled through same by dampers. Also, in second and third chambers I have vents controlled by dampers for increasing draft in last chamber, and relieving pressure in second chamber.

The chambers of the spark arrester, M , M^1 , M^2 , are of considerable volume, being bounded on the lower side by the curved surface of the boiler, extending around on each side as low as desired for area and convenient regulation of sparks, and draft. The curvature of the front chamber M is of advantage in directing backward the flames, unburned gases and unconsumed particles of smoke, this purpose being facilitated also by the means elsewhere described for regulating the draft. Any combustible matter carried into the ash pan by the draft is returned to the fire and given another chance to burn. Again, the sparks and the exhaust steam are so mixed as to extinguish the sparks or render them harmless before they reach the open air. In this event the ash pan acts as a spark arrester.

My apparatus as a whole presents a large area and exercises a considerable control over the exhaust and draft, and tends to avoid back pressure.

It will be noticed that my invention comprises a combustion chamber arranged at a suitable point between the ends of the boiler and in communication with the heating flues thereof and partitioned to divide the products of combustion. This is effected in the construction shown in Fig. 1 by the plates G and G' in the chamber E and the trans-

verse plates in the chamber F and this construction may be preferred in the manufacture of new boilers.

- The construction shown in Figs. 10, 11 and 12 may be preferred in the repairing and reconstruction of old boilers. In this construction the combustion chamber connects at its rear end with all of the heating flues P of the series in rear of the chamber O so that all of the flues at the rear of the boiler discharge at their forward ends into the rear end of the chamber O. Manifestly this construction shown in Fig. 10 may be employed with any desired form of fire box. Within the chamber O is provided a partition Q which may be made of sheet metal or fire brick shown in detail in Fig. 12 and Fig. 13 inclining upwardly from its lower to its upper end and preferably rounded from side to side as best shown in Fig. 12 so that the products of combustion discharged by the rear flues P to the rear end of the chamber O will be discharged from the front end of said chamber O at the upper portion thereof, the products thus collecting in the upper series of flues R and discharging at the front ends of said flues R into the smoke box whence they will be returned by the lower flues S into the lower end of the chamber O and will be directed by the regulating plates T in the lower portion of the chamber O to the intermediate flues U from which they are discharged into the smoke chamber and then into the stack subject to the action of the exhaust as will be understood from Fig. 10. Manifestly the partition plates Q may be of any shape to suit the manner in which the flues are divided. As will be understood from Fig. 10, this combustion chamber O may be used without any chamber such as the chamber E shown in Fig. 1 and it will operate to control and direct the products of combustion in the manner desired. In the operation of this construction shown in Fig. 10, the flames from all the flues in rear of the chamber O discharge into said chamber and pass thence through the upper series of flues R and thence back through the flues S in the lower end of the chamber O and thence forward through the intermediate flues O to the smoke chamber in smoke box, thence to the stack. At the lower end of the chamber O I provide means at V to permit the introduction of air and for regulating the introduction of such air, the said means being substantially the same as the air introducing devices shown at E⁵ in Fig. 1.

A man hole may be provided on the front side of the chamber as shown in Figs. 1 and 10.

Within the smoke box at the front of the boiler, I arrange at the base of the stack 4 and in communication therewith and with the center series of flues what, for con-

venience of reference, I term a smoke chamber which, as best shown in Fig. 3, widens outwardly at its lower end in such manner as to receive the products received from the central series of flues and direct the same to the stack 4. This smoke chamber is arranged inside of the main smoke box and receives the discharge from the nozzle and from the center flues, and empties its contents into the stack 4. The smoke chamber is for the purpose of receiving the draft and products of combustion from the center series of flues. Manifestly this smoke chamber at the base of the stack 4 may be made in any desirable shape to serve its purpose and may be extended straight across the smoke box, straight or setting level under the stack 4, straight across to sides, connecting to nozzle on bottom side as shown, or curving around to each side and passing to the sides of the smoke box in any circle as may be desired, with a man hole in front as shown in Figs. 1 and 10 for entering said chamber for any purpose, with adjustable sheets or plates at the bottom of said chamber, see Fig. 1, for the purpose of regulating the draft in the main smoke box in front and behind the nozzle, and the partition sheets inside the combustion chamber to be made in accordance with the shape of this chamber that connects to the upright stack 4 for receiving draft through center series of flues. This smoke chamber at the base of the stack 4 and resting upon the nozzle is also utilized, in the construction shown in Fig. 10, for receiving the exhaust from the nozzle at the bottom and the flames or products of combustion through the middle series of the flues. This middle series, as shown in Fig. 10, may be spaced off right straight through the center of the boiler from one side to the other or arranged in any other convenient form. It will be noted that the main smoke box rests upon the nozzle, and upon the top side is connected to the stack. I do not wish to be restricted, however, to any special shape for the smoke chamber, as it may be shaped to suit the arrangement of the flues, divided in three series with the central series discharging into it. It will also be noted that the smoke chamber is bolted to the flange of the nozzle with hole cut out for the exhaust to pass through and extending from the flue sheet out in front of the nozzle with adjustable sheets or plates on its bottom in front and behind the nozzle.

The top sheet of the smoke chamber extends from the flue sheet over the central series of flues forward above the nozzle with hole cut out directly over the center of the nozzle for the upright stack 4 to be riveted to, this stack 4 being intended to carry away the products discharged into the smoke chamber. On the front side of

6
said smoke chamber is bolted a sheet forming the front side of the chamber and having a hole cut out with a man hole in it for the purpose of entering this chamber for 5 any desirable purpose. Looking at this chamber inside of smoke box from the front end of boiler, the width, height, shape and size of this chamber depends on the way the central or middle section or series of 10 flues are divided off from the upper and lower series for convenience and for the purpose of receiving the draft or contents from the fire box or combustion chamber through the central series of flues. 15 In Fig. 13 I show a combustion chamber disposed in the fire box and this construction may be used when desired, and when used the combustion chamber may be made of any suitable fire brick or similar material. 20

I claim:

1. A steam boiler having heating flues arranged in three series, with an upper series conducting the products of combustion forwardly from the fire box, a lower series returning the said products and an intermediate series receiving the products from the lower series and conducting the same forwardly between the upper and lower series to a delivery point, substantially as set forth. 25
2. A steam boiler having heating flues and a combustion chamber and having its heating flues divided into upper, lower and intermediate series, a smoke box in advance 30 of the boiler and receiving the products discharged by the upper series of flues and delivering the same to the lower series of flues with the latter discharging into the combustion chamber and the intermediate flues 35 extending forwardly from the combustion chamber, a smoke chamber to which the intermediate flues discharge, an exhaust nozzle discharging into such chamber and a stack 40 leading from the chamber, substantially as 45 set forth.
3. A steam boiler having heating flues and a combustion chamber divided into three different sections, with each section communicating with a series of the flues, the said combustion chamber having an opening and having its partitions provided with openings and with closures therefor, with the partitions and the closures so formed as to permit their 50 insertion or withdrawal through the opening leading to the combustion chamber, substantially as set forth. 55
4. A steam boiler having heating flues and a main combustion chamber and an intermediate combustion chamber located within 60 the boiler, the heating flues of the boiler being divided into three series, an upper, lower and intermediate series, with the lower and intermediate series communicating 65 with the main combustion chamber and the upper, lower and intermediate series 70

communicating with the intermediate combustion chamber, the latter being divided into sections corresponding with the several series of flues, substantially as set forth. 75

5. In a boiler the combination of a boiler shell, a plurality of groups of flues within said shell and receiving the flames and gases in succession, flue sheets spaced apart to form a combustion chamber and the flues extending in opposite directions from said 80 sheets, and partitions dividing said chamber into separate passages that communicate with the opposite flues in said flue sheets for the passage of flames and gases in traveling through the flues in succession. 85

6. In a boiler the combination of a boiler shell containing a smoke box, a chamber within the smoke box, and having a discharge outlet, groups of flues in communication with the interior of the smoke box, but not with said chamber, respectively leading to the chamber and leading from the chamber and flues communicating with said chamber with which the flues leading from the smoke box communicate. 90

7. In a boiler the combination of a combustion chamber within the boiler formed of a cylindrical shell, a flue sheet and a rear head, a fire box flue sheet, said head being stayed to said fire box flue sheet and spaced therefrom, and the cylindrical shell being extended beyond said head to the flue sheet of the fire box with cut away portions for the circulation of water between the head and the fire box flue sheet, a draft plate projecting from the combustion chamber flue sheet and having an adjustable member to regulate the draft, and groups of flues connected with the combustion chamber flue sheet and opening into the latter respectively above and below said draft plate. 95

8. In a boiler the combination of a boiler shell and a combustion chamber consisting of a cylindrical shell and front and rear flue sheets, said shell having a flange at each 100 end, the flanges being riveted to the front and rear flue sheets, respectively, said shell being of less diameter than the boiler shell and spaced therefrom, and the front and rear flue sheets extending beyond the cylindrical shell and to the boiler shell and having flanges riveted to the boiler shell. 115

9. In a boiler the combination of three groups of flues receiving the flames and gases in succession, said groups being arranged as upper, lower and intermediate, a smoke box, a stack, an exhaust nozzle, and a chamber within the smoke box in communication with the exhaust nozzle and with said stack, the upper and lower groups of flues 120 being in communication with the smoke box, and the intermediate group discharging into said chamber. 125

10. In a boiler, the combination of a fire box, heating flues arranged in upper, lower 130

and intermediate groups, a smoke box into which the flues of the upper group discharge, and with which the inlet ends of the lower group communicate, a chamber within said smoke box; an exhaust nozzle communicating with said chamber, a combustion chamber secured to said fire box and communicating with the lower group of flues at their discharge ends and with the intermediate group of flues at their inlet ends, and an outlet from said smoke box chamber in communication with the discharge ends of the intermediate group of flues.

11. In a boiler the combination of a fire box, heating flues arranged in upper, lower and intermediate groups, a smoke box into which the flues of the upper group discharge, and with which the inlet ends of the lower group communicate, a chamber within said smoke box, an exhaust nozzle communicating with said chamber, a combustion chamber circular in cross section and communicating with the lower group of flues at their discharge ends and with the intermediate group of flues at their inlet ends, and an outlet from said smoke box chamber in communication with the discharge end of the intermediate group of flues.

12. In a boiler the combination of a fire box, rear and front chambers, a group of flues leading from the fire box to the forward chamber in the upper part of the boiler, a group of flues leading from the forward chamber to the rear chamber in the lower part of the boiler, and an intermediate group of flues leading from the upper part of the rear chamber forward to the discharge.

13. In a boiler the combination of a fire box, rear and front chambers, a group of flues leading from the fire box to the forward chamber in the upper part of the boiler, a group of flues leading from the forward chamber to the rear chamber in the lower part of the boiler, an intermediate group of flues leading from the upper part of the rear chamber forward to the discharge, and a combustion chamber intermediate said forward and rear chambers and communicating with all of said flues.

14. In a boiler the combination of a fire box, rear and front chambers, a group of flues leading from the fire box to the forward chamber in the upper part of the boiler, a group of flues leading from the forward chamber to the rear chamber in the lower part of the boiler, an intermediate group of flues leading from the upper part of the rear chamber forward to the discharge, and a combustion chamber intermediate said forward and rear chambers and communicating with all of said flues, and comprising a plurality of independent compartments.

15. In a boiler the combination of a fire box, rear and front chambers, a group of flues leading from the fire box to the forward chamber in the upper part of the boiler, a group of flues leading from the forward chamber to the rear chamber in the lower part of the boiler, an intermediate group of flues leading from the upper part of the rear chamber forward to the discharge, a boiler shell, a man-hole tube leading from the boiler shell to said rear chamber, an air feeding tube extending through the man-hole cover and man-hole tube, and means for regulating the supply of air to said rear chamber.

16. In a boiler the combination of heating flues arranged in upper, lower and intermediate groups, a smoke box having an inner chamber, a stack leading from an opening in the top of said chamber through an opening in the top of the smoke box, an exhaust nozzle leading to an opening in the bottom of said chamber and delivering its discharge to the lower end of said stack, and a combustion chamber that is in communication with the inlet ends of the intermediate group of flues, the outlet ends of said group being in communication with the internal chamber of the smoke box, and said smoke box being in communication with the outlet ends of the upper group of flues and the inlet ends of the lower group of flues, and the outlet end of the lower group of flues being in communication with said combustion chamber.

17. In a boiler the combination of heating flues arranged in groups, one above another, a smoke box having an interior chamber, the back wall of the smoke box being a flue sheet for said heating flues, the upper and lower groups of flues opening into the smoke box outside of said inner chamber, and the inner group of flues opening into said chamber, a stack extending upward from the inner chamber and opening through the top of the smoke box, an exhaust nozzle passing from an opening in the bottom of the smoke box to an opening in the bottom wall of the inner chamber, and adjustable plates extending into the smoke box from the bottom wall of the inner chamber.

18. In a boiler the combination of heating flues arranged in upper, lower and intermediate groups, a smoke box having an inner chamber, a stack leading from an opening in the top of said chamber through an opening in the top of the smoke box, an exhaust nozzle leading to an opening in the bottom of said chamber and delivering its discharge to the lower end of said stack, and a combustion chamber that is in communication with the inlet ends of the intermediate groups of flues, the outlet ends of said group being in communication with the internal chamber of the smoke box, and said smoke

box being in communication with the outlet ends of the upper group of flues and the inlet ends of the lower group of flues, and the outlet end of the lower group of flues being 5 in communication with said combustion chamber, and a man-hole in the front wall of the inner chamber.

19. In a boiler the combination of a fire box having its front wall formed of a flue sheet, heating flues arranged in groups one above another, the flues of one of said groups passing through said flue sheet, draft regulating plates, a combustion chamber formed of a cylindrical shell that at one end 10 bears against said flue sheet, a flue sheet at the front end of said cylindrical shell, and a head at the rear end spaced from the fire box flue sheet, said shell having circulation openings into the space between the fire box 15 flue sheet and said head, the portion of the shell extending from the head to the fire box flue sheet forming a brace for the fire box flue sheet, stay bolts connecting said head and the fire box flue sheet, the flues of 20 the lower and intermediate groups opening 25 through said combustion chamber flue sheet, means for directing flames and gases from the upper group of heating flues to the lower group, and means for the discharge of 30 flames and gases from the inner group of flues.

20. In a boiler the combination of a fire box having its front wall formed of a flue sheet, heating flues arranged in groups one above another, the flues of one of said groups passing through said flue sheet, a combustion chamber formed of a cylindrical shell that at one end bears against said flue sheet, a flue sheet at the front end of said cylindrical shell, and a head at the rear end 35 spaced from the fire box flue sheet, said shell having circulation openings into the space between the fire box flue sheet and said head, the portion of the shell extending from the 40 head to the fire box flue sheet forming a brace for the fire box flue sheet, stay bolts connecting said head and the fire box flue sheet, the flues of the lower and intermediate groups opening through said combustion 45 chamber flue sheet, draft regulating plates mounted on the combustion chamber flue sheet between the lower and intermediate groups of flues, means for directing 50 flames and gases from the upper group of heating flues to the lower group, and means for the discharge of flames and gases from the inner group of flues.

21. In a boiler the combination of a fire box, a smoke box, a chamber within the same 60 three groups of heating flues, one of which groups extends from the fire box to the smoke box, a combustion chamber communicating with the smoke box through another group of flues, the third group of flues extending from the combustion chamber to the

inner chamber of the smoke box, and a stack 70 communicating with the interior of said inner chamber, a space being left between the front of the inner box and the front wall of the smoke box for the passage of flames and gases from the group of flues leading from the fire box to the group of flues leading to the combustion chamber.

22. In a boiler the combination of a smoke box, one wall of which is a flue sheet, heating flues arranged in a plurality of groups, one above another, said smoke box having an inner chamber, a stack leading from said inner chamber, an exhaust nozzle leading into said inner chamber and means connecting the outer wall of said inner chamber with said flue sheet, the flues of certain of said groups communicating with the smoke box outside of said inner chamber, and the flues of another group communicating with the interior of said chamber.

23. In a boiler the combination of a smoke box, one wall of which is a flue sheet, heating flues arranged in a plurality of groups, one above another, said smoke box having 90 an inner chamber, a stack leading from said inner chamber, an exhaust nozzle leading into said inner chamber, means connecting the outer wall of said inner chamber with said flue sheet, the flues of certain of said groups communicating with the smoke box outside of said inner chamber, and the flues of another group communicating with the interior of said chamber, and adjustable draft plates secured to the outside wall of 95 said inner chamber.

24. In a boiler the combination of a combustion chamber having a wall formed by a flue sheet, groups of heating flues secured to said sheet, and an adjustable draft plate 105 extending from said flue sheet into the combustion chamber to control the passage from one group of flues to another group of flues.

25. In a boiler the combination of a front flue sheet, a rear flue sheet, a combustion 110 chamber having a wall formed of a flue sheet, a group of flues establishing communication between the spaces outside of the front and rear flue sheets, a group of flues establishing communication between the 115 outside of the front flue sheet and the interior of the combustion chamber, and a group of flues establishing communication between said combustion chamber and a point of discharge in advance of said front 120 flue sheet.

26. In a boiler the combination of a front flue sheet, a rear flue sheet, a combustion chamber having a wall formed of a flue sheet, a group of flues establishing communication between the spaces outside of the front and rear flue sheets, a group of flues establishing communication between the outside of the front flue sheet and the interior of the combustion chamber, a group 125 130

of flues establishing communication between said combustion chamber and a point of discharge in advance of said front flue sheet, and means for supplying air from outside 5 the boiler to said combustion chamber.

27. In a boiler the combination of a shell, a combustion chamber within the shell, a tapering tube passing through an opening in the shell and leading to the interior of 10 the combustion chamber, the smaller end of said tube being inward and having an outward flange in contact with the outer wall of the combustion chamber, and a flange around the opening in the shell through 15 which the tube passes and to which the larger end of the tube is secured, said tube being removable bodily through the shell opening.

28. In a boiler the combination of an 20 outer shell consisting of a front cylindrical section, a rear substantially cylindrical section, and a frusto-conical intermediate section, a fire box that is arc-shaped in cross section and is within the rear section of the 25 boiler shell, the top side of the fire box being substantially in line with the top side of the front cylindrical section of the boiler shell, a flue sheet in the forward end of said cylindrical section, a rear flue sheet in the 30 forward end of the fire box, and heating flues connected with said flue sheets in the upper parts thereof, the rear boiler section being larger than the inclosed fire box so as to provide water and steam space above the 35 fire box.

29. In a boiler the combination of a shell composed of a cylindrical section, a frusto-conical section and an arc-shaped section, the cylindrical section being at the front of 40 the boiler and the arc-shape section at the rear, the diameter of the arc-shape section being greater than that of the cylindrical section, and the small and large ends of the frusto-conical section being respectively 45 connected with the cylindrical front section and the rear arc-shape section, a flue sheet in the forward end of the front section, a rear flue sheet, flues connected with said sheets, a fire box shell arc-shape in cross section 50 whose front end is formed by said rear flue sheet, the top of said fire box shell being substantially in line with the top of the front cylindrical section, and a mud frame that forms with the arc-shape boiler section 55 the rear portion of the boiler shell, the front portion of the mud frame being curved downward and extending across to each side of the arc-shape shell section.

30. In a boiler the combination of a shell 60 that comprises a frusto-conical section and an arc-shape section, a mud frame that extends along the arc extremities of the arc shape section and extends between said ex-

tremities at the forward end and is curved downward on a radius the same as that of 65 the arc shape section to form a complete circular shape, and a connection between the frusto-conical section and the arc shape section and the mud frame.

31. In a boiler the combination of a shell 70 that comprises a frusto-conical section, an arc shape section, and a cylindrical section that forms the front of the boiler shell and is of less diameter than the arc-shape section, a mud frame that extends along the 75 arc extremities of the arc shape section to form a complete circular shape, and a connection between the frusto-conical section and the arc shape section and the mud frame.

32. In a boiler the combination of a shell 80 that comprises a frusto-conical section and an arc-shape section, a mud frame that is approximately U-shape and extends along the arc extremities of the arc shape section and extends between said extremities at the 85 forward end and is curved downward on a radius the same as that of the arc shape section to form a complete circular shape, and a connection between the frusto-conical section and the arc shape section and the mud 90 frame.

33. In a boiler the combination of a fire box, a shell section arc shape in cross section that extends over and at each side of the fire box, a mud frame connecting the sides of 95 said shell and the fire box and extending in a curve at its front end between the side extremities of said shell section, and a shell section that is circular in cross section and is secured to the arc shape shell section and 100 said mud frame.

34. In a boiler the combination of a substantially arc shape fire box shell, a flue sheet in its forward end, a substantially arc shape shell extending over and at each side 105 of the fire box shell, a mud frame extending between the shells at the bottom of the sides of the outer shell and extending across under the flue sheet of the fire box, a cylindrical shell forming the front portion of the 110 boiler shell, and of less diameter than the shell extending about the fire box, a flue sheet secured in said cylindrical shell, a frusto-conical shell secured at its small end 115 to said cylindrical shell and at its large end to the arc shape fire box inclosing shell, said large end extending over and at each side of the fire box and to the mud frame, the lower side of said frusto-conical shell being carried downward and rearward from said 120 cylindrical shell and connected with said mud frame.

CHARLES W. CROWELL.
